UNITED STATES PATENT OFFICE.

IRA A. WEAVER, OF SPRINGFIELD, ILLINOIS, ASSIGNOR TO SATTLEY MANUFACTURING COMPANY, OF SPRINGFIELD, ILLINOIS, A CORPORATION OF ILLINOIS.

WHEEL-PLOW.

SPECIFICATION forming part of Letters Patent No. 715,783, dated December 9, 1902.

Application filed August 8, 1902. Serial No. 118,955. (No model.)

To all whom it may concern:

Be it known that I, IRA A. WEAVER, of the city of Springfield, county of Sangamon, and State of Illinois, have invented certain new and useful Improvements in Wheel-Plows, of which the following is a specification.

This invention is particularly applicable to disk plows; but its utility extends to some extent to wheel-plows of the ordinary share and moldboard type.

Proper operation of wheel-plows depends largely on the lead of the caster-wheels, and various devices have been used to set the rear caster-wheel at the proper angle or lead to resist landward thrust of the soil and to hold the wheel in position as the plow travels across the field in practical operation. The rear caster-wheel of a modern wheel-plow is journaled on a laterally-extended spindle of a rearward extension of a post pivoted vertically in the plow-frame, and the wheel is inclined with its tread presented toward the land. The plows take the resistance of the soil in an oblique direction, and the stress is exerted landward and backward on the soil-turning surfaces of the plows. The effect of the stress is to carry the plows landward, and it is the function of the caster-wheels, particularly the rear one, to neutralize the sidewise pressure of the soil. When left to itself, the caster-wheel journaled in the rear end of the plow-frame will swing freely on its vertical pivot and permit the plows to run to land, and controlling appliances are made with a view to restraining the lead of the wheel toward the land. No provision is needed to restrain the rear caster-wheel against leading from the land, as that tendency is never developed in plowing and is harmless at other times; but whatever restraint is provided against landward lead of the wheel should be removed while the plow is turning around. While turning in one direction, the rear caster-wheel may swing backward away from the controlling restraint; but in turning in the other direction the controlling restraint would be a serious impediment, and in practical operation it is found safer and more convenient to remove all restraint to free side swing of the rear caster-wheel preparatory to turning around.

Various means have been devised for locking the rear caster-wheel while plowing and relieving it while turning around; but the availability of the post of the front caster-wheel for transmitting controlling restraint to the rear caster-wheel and relieving such restraint automatically has been generally recognized and approved. The post of the front caster-wheel partakes of the swing of the tongue in turning around and remains very nearly stationary in its bearings while the team is traveling straight forward, and as those are approximately the conditions demanded of the rear caster-wheel the advantages of a controlling connection between the two caster-wheel posts is obvious.

In developing a connection between the two caster-wheel posts many experiments have been tried and many difficulties have been overcome, until it is now generally conceded that the proper controlling connection is one in which the thrust of the rear caster-wheel, developed by soil-pressure, is directed against the post of the front caster-wheel. This arrangement prevents the thrust of the rear caster-wheel from developing side swing in the tongue. It also almost entirely prevents the transmission to the rear caster-wheel of sway of the team developed in walking along, and it represents the advanced type of caster-controllers. It happens, however, that there is more or less spring in plow-frames and more or less looseness in bearings. There is also considerable variation in the conditions of soils, and all these combine to interfere with accurate control of the rear caster-wheel from the front caster-wheel post. These disadvantages are more pronounced in disk plows than in other wheel-plows, owing probably to the difference in the construction of the frames and the general arrangement of the parts; but they exist to some extent in all wheel-plows having caster-wheels, and their removal constitutes the principal object of this invention.

To attain my object in regard to properly controlling the rear caster-wheel, I extend a tie-brace from one caster-wheel post to the other and take the stress of the caster-controller off the plow-frame. The brace is made longitudinally adjustable or extensible and

contractible preferably by means of a turn-buckle. It is placed as close to the caster-controller connections as is convenient, and its connections with the posts are, to get best results, entirely independent of the plow-frame. When the brace is properly adjusted and the caster-controller properly arranged, the thrust of the controller-rod is taken off the plow-frame by the brace, and the action of the caster-controller is independent of loose bearings and of spring in the frame. The effect of the brace is to make the caster-controlling mechanism, of which the brace forms a part, a self-contained structure free from outside influences and independent of varied conditions of soils. The brace also provides means for increasing the accuracy of adjustment of the caster-controller to give the rear wheel proper lead. As there is always some looseness in the post-bearings, movement of the posts toward and from each other affects the relation of the caster-wheels to the controlling-rod, and the turnbuckle of the tie-brace permits nice adjustment of the posts. The tie-brace is by itself quite effective in wheel-plows of the share and moldboard type and reasonably so in wheeled disk plows; but I find that the result can be improved in disk plows by providing a special draft-hitch, through which the lead of the front caster-wheel is governed. The draft-hitch comprises a draft-bar or stub tongue, which is free to move backward at its connection with the plow-frame and which has a pair of hitch-bearings, one on each side of the line of draft. An arm on the post of the front caster-wheel is connected with the draft-bar in front of the draft-hitch, and so long as the team is pulling on the plow the draft-bar and the front post are held against side swing by the stiffness generated from the two separated draft-hitches. The rigidity imparted to the front post by the pull of the team is transmitted to the controlling-rod, and the rear caster-wheel is steadied thereby. When an end of the field is reached and the team is turned sidewise, the draft-bar swings sidewise and slightly rearward, with one of its draft-hitches for a pivot, and imparts its sidewise swing to the front caster-wheel post, with the result that the controlling device for the rear caster-wheel is rendered inoperative and the rear caster-wheel is left free to swing around with the plow-frame.

Another object of my invention is to provide means for transmitting side swing from the draft-bar to the post of the front caster-wheel in the same horizontal plane regardless of the vertical shift of the post in its bearings in the frame, and still another object is to provide improved means for shifting the rear caster-wheel vertically with relation to the frame.

In the drawings forming part of this specification, Figure 1 is a plan of so much of a disk plow as is needed to explain my improvements. Fig. 2 is a side elevation of the struc-

ture included in Fig. 1 with the addition of a lift-lever for the front caster-wheel. Fig. 3 is a detail in front elevation of the bearing-bracket for the post of the front caster-wheel. Fig. 4 is a plan of the arm on the post of the front caster-wheel which takes motion from the tongue or draft-bar and imparts it to the post. Fig. 5 is a detail of a stepped collar which is used to vary the height of the rear end of the frame.

The plow-frame may be constructed in various ways; but in this instance it is composed of a front cross-bar 1 and bars 2, connected rigidly together and to the front bar and shaped to properly carry the plow-disks 3. The post 5 is pivoted in the rear end of the plow-frame. It has a rearward extension 4, and a spindle turns sidewise from the rearward extension to form a bearing for caster-wheel 6. The post 8 for the front caster-wheel 9 is journaled in a bracket 26 on cross-bar 1. An arm 10 is rigidly attached to the upper end of post 8, and it extends rearward when the plow is in operative position. An arm 7 is rigidly attached to the upper end of post 5, and it extends outward with relation to the land when the plow is in operation. A sleeve 11 is pivoted in the swinging end of arm 7. A controlling-rod 14 is pivotally connected with the swinging end of arm 10. It extends through sleeve 11, and it has a set-collar 15, which bears normally against sleeve 11. A brace-rod 12 connects post 8 with post 5. It is preferably placed just below arms 10 and 7 in direct pivotal connection with the posts, and it is made in two parts or otherwise formed to permit lengthwise adjustment. As a matter of preference the two parts of the brace are connected by means of a turnbuckle, as 13, as this construction provides a strong brace capable of precise lengthwise adjustment.

The draft-bar 16 is slotted lengthwise at its rear end, as shown at 18, to fit loosely over a bolt 17, projecting upward from a plate on the cross-bar 1 of the frame, and it has hitch-bearings 19 and 20, adapted to engage the front cross-bar, one on each side of the line of draft. In this instance the hitch-bearings are secured rigidly to the draft-bar and project downward behind the cross-bar of the frame; but their construction is immaterial so long as they form an elongated or two-part bearing, which tends to hold the draft-bar stiff with relation to the plow-frame, so far as side motion is concerned, while the team is pulling the plow by a connection made with the forward end of the draft-bar.

The bracket 26 is made with a recess 26^a cut through its post-bearing part, and the vertical part of post 8 has a key-seat groove throughout a part of its length. (See Fig. 3.) An arm 21 fits onto the post 8 in the recess 26^a of bracket 26, and it has a key 27, (shown in Fig. 4,) which engages the groove 8^a of post 8. The arm 21 is preferably formed with an enlarged vertical slot 21^a in Fig. 4.

to readily admit the key 27, and the key is held in position by means of a suitable bolt. The arm 21 extends forward parallel with hitch-bar 16, and a rod 22 connects the draft-bar with the arm.

5 A notched sector is set onto the upper end of post 8, a lock-lever 23 is pivotally connected with the sector, and a link 24 connects an extension of lever 23 with a lug 25 on bracket 26. By swinging the lock-lever up and down the post and the wheel thereon are raised and lowered with relation to the bracket 26 and other parts of the frame, and during such operation the post-controlling arm 21 10 slides lengthwise of the post while maintaining its rotatory connection therewith and keeping up its horizontal relation to the draft-bar. The spline and feather or key and groove are typical of mechanical means for maintaining a connection between the post and the arm while permitting the arm to rise and fall with the draft-bar, and it is obvious that other mechanical means may be used to get the same result.

25 A stepped collar 28 fits on the rearward extension of the rear post 5 beneath the frame, and it provides means for raising or lowering the rear end of the plow-frame with reference to the post. The collar is shown in detail in 30 Fig. 5, and it has a plurality of convex bearing-surfaces *a*, *b*, and *c* at different distances from its upper end, each adapted to rest on the rearward extension of the post. A set collar on the post above the frame provides 35 means for holding the frame seated on the collar; but by loosening the set collar and raising the frame the stepped collar may be turned to bring either of its bearing-surfaces over the extension of the post, and the frame 40 may thus be raised or lowered within certain degrees.

By causing arm 21 to rise and fall with the draft-bar 16 the rod 22 is able to hold the arm always at the same distance from the draft-bar and give always the same lead to the 45 front caster-wheel while plowing.

I claim—

1. In a plow having caster-wheels on vertical posts, the combination, with the posts 50 of the caster-wheels, of a restraining appliance for the rear caster-wheel controlled from the front post, and a brace connecting one post with the other.

2. In a plow having caster-wheels on vertical posts, the combination, with the posts 55 of the caster-wheels, of a restraining appliance for the rear caster-wheel controlled from the front post, and a longitudinally-adjustable brace connecting one post with the other.

60 3. In a plow having caster-wheels on vertical posts, the combination, with the posts of the caster-wheels, of a restraining appliance for the rear caster-wheel controlled from the front post, and a two-part brace-rod 65 joined by a turnbuckle and connected pivotally with the posts.

4. In a plow having caster-wheels on ver-

tical posts, the combination, with the posts of the caster-wheels, of an arm on the rear post normally extending sidewise, an arm on the 70 front post normally extending rearward, a strut-brace connecting the swinging ends of the arms, and a tie-brace connecting one post with the other.

5. In a wheel-plow, the combination of a 75 frame structure, a plow, secured to the frame, caster-wheels on posts journaled in the frame and extended above the same, an arm on the upward extension of the rear post normally extending sidewise, an arm on the upward 80 extension of the front post normally extending rearward, a strut-brace connecting the swinging ends of the arms, and a tie-brace connecting the upward extension of one post with the upward extension of the other post. 85

6. In a wheel-plow the combination of a 90 plow-frame, a draft-bar conjoined to the frame and having a limited amount of back and forward motion at its conjunction with the frame, means for holding the draft-bar 95 against side motion, a pair of draft-bearings on the rear end of the draft-bar, one on each side of the line of draft, and a team-hitch at the front end of the draft-bar, substantially as described.

95 7. In a wheel-plow, the combination of a plow-frame, a draft-bar free to move backward at its conjunction with the frame and having a pair of draft-bearings one on each side of the line of draft, means for holding 100 the draft-bar against side motion, a caster-wheel on a vertical post pivoted in the plow-frame, and a controlling-link between the draft-bar and the post of the caster-wheel, substantially as described. 105

8. In a wheel-plow, the combination of a plow-frame, a draft-bar free to move backward at its conjunction with the frame and having a pair of draft-bearings one on each side of the line of draft, means for holding 110 the draft-bar against side motion, a front 115 caster-wheel and a rear caster-wheel each journaled on a vertical post pivoted in the frame, a controlling connection between the posts of the caster-wheels and a connection between the draft-bar and the post of the front 120 caster-wheel.

9. In a wheel-plow, the combination of a plow-frame, a draft-bar free to move backward at its conjunction with the frame and 125 having a pair of draft-bearings one on each side of the line of draft, means for holding the draft-bar against side motion, a front 130 caster-wheel and a rear caster-wheel each journaled on a vertical post pivoted in the frame, a controlling connection between the posts of the caster-wheels, a link between the draft-bar and the post of the front 135 caster-wheel, and a tie-brace between the upper ends of the posts.

10. In a wheel-plow, the combination of a frame, a hitch-bar pivotally connected with the front of the frame, a caster-wheel post pivoted in vertical bearings in the frame and

slidable lengthwise of the bearings, means for shifting the post lengthwise in its bearings, an arm slideable on the post and held against rotation independent thereof, and a link connecting the arm with the hitch-bar.

11. In a wheel-plow, the combination of a frame, a hitch-bar pivotally connected with the front of the frame, a bracket attached to the frame, such bracket being vertically tubular and cut away between its ends, a caster-wheel post extending through the tubular part of the bracket, such post being grooved lengthwise, an arm on the post in the cut-away part of the bracket, a key in the arm 15 engaging the groove of the post, means for

moving the post lengthwise of its bearings, and a link pivotally connecting the arm with the hitch-bar.

12. In a wheel-plow, the combination of a frame, a caster-wheel post journaled in the frame and extended horizontally below the frame, and a stepped collar between the frame and the horizontal extension of the post, for varying the height of the frame.

In testimony whereof I sign my name in the presence of two subscribing witnesses.

IRA A. WEAVER.
